ATTORNEY

UNITED STATES PATENT OFFICE.

ALBERT F. FROUSSARD, OF ST. LOUIS, MISSOURI.

GRINDER.

Application filed March 24, 1923. Serial No. 627,267.

To all whom it may concern:

Be it known that I, ALBERT F. FROUSSARD, a citizen of the United States, residing at the city of St. Louis, in the State of Missouri, have invented certain new and useful Improvements in Grinders, of which the following is a specification.

This invention relates to a device for finishing or highly polishing the internal 10 cylindrical surfaces of engine cylinders and the like after the same have been bored, and has for one of its objects to provide a safety stop for limiting the depth of travel of the hone in the cylinder and thereby prevent 15 damage to the hone on account of its accidentally encountering obstructions beyond the bore of the cylinder.

Another object is to provide means for holding the blocks of abrasive material so 20 that the same are readily removable for replacement, but are, also, retained in the hone when the same is withdrawn from the cylinder.

A further object is to provide efficient 25 means for supplying the abrasive with lubricant.

Other objects are to arrange for long 30 springs, which are capable of great variation in length without taking on a permanent set and to provide a shield to protect the abrasive material from the cutting action of the spring.

In the accompanying drawings forming 35 part of this specification, in which like numbers of reference denote like parts wherever they occur,

Figure 1 is an elevation of the complete hone;

Figure 2 is a top view of the same;

Figure 3 is a transverse section taken on the line 3—3 of Figure 1;

Figure 4 is a bottom view;

Figure 5 is an enlarged section taken on the line 5—5 of Figure 1;

Figure 6 is a perspective view of one of the blocks of abrasive material; and

Figure 7 is a perspective view of the shield for protecting the abrasive blocks from the cutting action of the springs.

In the practice of my invention I provide 50 a holder 1 having a cylindrical portion 2, plane sides 3, slots 4, and a hole 5 open at ends 6 and 7. End 6 is screw-threaded at 8 for the reception of a cap 9, having a socket 55 10 for the insertion of a wrench whenever

necessary for the removal or replacement of said cap 9. The holder 1 is preferably of aluminum to secure lightness and consequently a minimum of vibration.

A shank or spindle 11 for driving the 60 holder 1 is provided at one of its ends with a reduced portion 12 for connection to an electric drill socket, lengthening bar, or other suitable connection to a source of power. A transverse hole 13 through shank 11 registers with a corresponding hole in the drill socket or other connection when the end of said socket abuts against shoulder 14 of shank 11. A pin passing through both holes secures shank 11 to said socket and causes 65 both to rotate in unison. Shank 11 enlarges at 15 for stiffness and enlarges further at 16 into flange 17, secured to end 7 of holder 1 by screws 18 passing through flange 17 and into tapped holes 19 in holder 1. 70

Hole 5 when closed at both ends 6 and 7 forms a pocket for the reception of kerosene or other suitable lubricant, which is supplied thereto through threaded opening 20 in flange 17, which opening 20 is normally closed by screw 21. The lubricant is exuded through openings 22 in holder 1 against the cylinder wall by the centrifugal force incident to the rotation of the holder 1. 75

Tubes 23, preferably steel, extend through 80 hole or pocket 5 and open at their opposite ends into their respective pair of diametrically opposed slots 4. The tubes 23 are secured to holder 1 by friction and by peening over their ends as indicated at 24. 85

Plates 25 are secured to the plane sides 3 by screws 26 and are provided with bent ends 27 projecting slightly beyond and perpendicularly to the sides of the slots 4. Blocks 29 of abrasive material fit in the slots 90 4 and have projections 30, which contact with the ends 27 of plates 25 and thereby limit the outward movement imparted to said blocks 29 by springs 31, interposed between each pair of diametrically opposed 100 blocks 29 and held in the tubes 23. The blocks 29 are protected from the cutting action of the springs 31 by shields 32 interposed between said springs 31 and blocks 29. The shields 32 are preferably formed of 105 sheet metal and have perpendicular projections 33 formed by displacing some of the metal by means of dies at 34. The blocks 29 can be withdrawn from the holder 1 at the end 6 after cap 10 has been removed, but 110

the shields 32 are retained in the slots 4 by the engagement of the projections 33 with the springs 23.

5 The depth of travel of the holder in the cylinder is limited by a safety stopping plate 35, adapted to engage the end of the cylinder and thereby prevent damage to the honer by running the same below the bottom of the cylinder. Plate 35 can be set on shank 11 to 10 accommodate different lengths of cylinders by a set-screw 36, which screws into hub 37, integral with plate 35.

15 The slots 4 are provided with ends 38, which, in conjunction with flange 39 of cap 9, prevent longitudinal movement of said blocks 29 in said slots 4.

20 Having thus described this invention, I hereby reserve the benefit of all changes in form, arrangement, order, or use of parts, 25 as it is evident that many minor changes may be made therein without departing from the spirit of this invention or the scope of the following claims.

I claim:

25 1. In a grinder, a spindle having an integral flange formed at one end thereof, a hollow head having a series of longitudinally extending slots formed therein secured to said flange and extending axially outwardly therefrom, a cap removably secured to the outer end of said head, said flange and cap adapting said head to carry lubricant, said head having a pair of openings formed in the inner wall of each slot, said openings 30 being adapted for receiving diametrically extending springs, an abrasive element positioned within each slot adapted to be forced outwardly therefrom by said springs, and means for permitting lubricant to be 35 discharged from said hollow head by centrifugal force.

40 2. In a grinder, a spindle having an integral flange formed at one end thereof, a hollow member secured to said flange and 45 extending axially outwardly therefrom, a cap removably secured to the outer end of said hollow member, said flange and cap adapting said hollow member to carry lubri-

cant, a plurality of tubes traversing the bore of said hollow member, a spring within each tube, a plurality of abrasive elements carried by said hollow member and forced outwardly by said springs, means for limiting the outward movement of said abrasive elements, and means for preventing said springs from directly engaging said element, said hollow member having a series of angularly arranged openings through which lubricant is discharged by centrifugal force during operation of said grinder.

45 3. In a grinder, a spindle, a hollow head adapted for carrying lubricant secured to said spindle, a plurality of tubes traversing the bore of said head, a spring within each tube, a plurality of abrasive elements carried by said head and forced outwardly by said springs, means for limiting the outward movement of said abrasive elements, means for preventing said springs from directly engaging said abrasive elements, and means 50 for permitting the discharge of lubricant from said head during operation of said grinder.

55 4. In a grinder, a holder presenting a tubular body having the lower portion of its outer surface indented with circumferentially spaced, longitudinally extending slots having their respective entrance-openings adjacent one end of the body and the upper portion of its outer surface pierced with 60 transversely extending oil-ports communicating with the hollow interior of the said body, blocks of abrasive material engaged in the said slots, a cap closing one end of the tubular body and having a flange projecting over the entrance-openings of the said slots to prevent withdrawal of the said blocks therefrom, a flange closing the other end of the said tubular body and having a filling opening thru which lubricant may be 65 supplied to the hollow interior of the said body, and a driving spindle mounted on the said flange.

70 In testimony whereof I hereunto affix my signature.

ALBERT F. FROUSSARD.
